UNITED STATES PATENT OFFICE.

JOSEPH SYLVAN, OF CICERO, ILLINOIS.

WINDOW CONSTRUCTION.

Application filed May 28, 1923. Serial No. 641,979.

This invention relates to improvements in window construction and consists of the matters hereinafter described and more particularly pointed out in the appended claims.

5 The object of the invention is to provide a relatively wide passageway between the meeting rails of the sash which may be opened for ventilation or may be closed when desired by an elongated plate or flap, 10 hinged along one edge to one of the meeting rails and having a weather proof engagement along its other edge with the associated meeting rail.

This object of the invention as well as the 15 many advantages thereof, will more fully appear as I proceed with my specification.

In the drawings:—

Figure 1 is a vertical sectional view 20 through a window embodying my improved construction.

Figure 2 is a vertical section on an enlarged scale through the meeting rails of the sash, with the parts shown in a position different from that in Figure 1.

25 Figure 3 is a horizontal sectional view through one side of the sash just above the meeting rails, the plane of the section being indicated by the line 3—3 of Figure 1.

Referring now in detail to that embodiment of the invention illustrated in the accompanying drawings:— 30 5 indicates as a whole a window frame which comprises, a head 6, a still 7, and jamb members 8, 8, all preferably made of sheet metal.

35 9 indicates the bottom or inner sash and 10 indicates the top or outer sash associated with the frame. Said sash as shown herein are made of sheet metal. The bottom sash comprises channel like side rails 11, 11, a

40 bottom rail 12 and a top rail 13, all of which are constructed to receive and hold the glass pane 14. The top sash also comprises channel like side rails 15, 15, a bottom rail 16 and a top rail 17, which are also constructed

45 to receive and hold a glass pane 18. The bottom rail 16 of the top sash, and the top rail 13 of the bottom sash, provide when the sash are in their closed position, what is commonly termed the "meeting rails" of 50 the sash.

Both sash are capable of a vertical sliding movement in the frame 5 and are guided in this movement by upright, laterally spaced apart channels 19 and 20 respectively, fixed to the inner surface of each jamb 8, said channels engaging in the channel like side

rails of the sash 9 and 10 respectively. Secured to the sill 7 and to the head 6 of the frame in the planes of the channels 19 and 20 are similar channels 21 and 22 respectively, which engage in the channel like bottom rail 12 of the bottom sash and channel like top rail 17 of the top sash, when both of said sash are closed, to make a wind and weather proof joint at said sill and head. Secured to the bottom rail 12 of the bottom sash is a handle 23 by means of which said sash may be raised and lowered.

The guide channels 19 and 20 are so arranged on the jambs that the sash are located in spaced vertical planes, thus leaving a passageway or space 24 between the sash at the meeting rails thereof. Means are provided to close said passageway 24 when desired and such means are as follows: 25 indicates an elongated plate or flap which is hinged along one margin as at 26 to the top rail 13 of the bottom sash 9, the axis of the hinged connection being preferably located in the median plane of the pane 14 in said bottom sash. The other or free margin of said plate is provided with a right angle flange 27 which is adapted when the flap is in its closed position, to engage in a trough like weather strip 28 carried by the bottom rail 16 of the top sash 10. Fixed to normally the under side of said elongated plate or flap, about midway between its longer edges is a weather strip 29. This weather strip includes a yielding flange 30 which is adapted, when the plate is in its closed position, to engage against a part of the top rail 13 to make a weather tight engagement against said rail.

Secured to the top surface of said plate 25, preferably near its ends, are knobs 31 by means of which the plate may be actuated, to swing it from its closed into its open position.

When the plate 25 is in one position, it bridges and closes the passageway 24 as shown in Figure 1, and when said plate is in its other position as shown in Figure 2, it opens said passageway to permit the entrance of air through said passageway between said meeting rails. Such air as enters through said passageway is directed upwardly toward the ceiling of the room. When the said plate is in its closed position, the weather strips 28 and 29 prevent the entrance of drafts between said meeting rails.

It is herein pointed out that said plate 25 in no manner interferes with the opening or closing movement of either sash, no matter whether said plate is in its open or its closed position.

Suitable coacting parts of locking devices (not shown) may be used between said rails, with one of said parts carried by the plate and the other carried by the bottom rail of the top sash.

My improved window construction provides a simple and efficient means for providing ventilation for the room in which it is used. The improved window is in no manner unsightly in appearance and does not interfere with the use of curtains, shades or screens, therefore, it is as well adapted for use in the home as in office buildings and the like.

While in describing my invention I have referred to certain details of mechanical construction and arrangement of parts, I do not wish to be limited thereto except as may be pointed out in the appended claims.

I claim as my invention:

1. The combination with an upper and lower window sash, said sash having rails adapted to meet when the sash are closed and being spaced apart to provide a ventilation passageway between them, means carried by the lower sash and adapted to be swung to a position to close said passageway or to a position to fully open the same, said means including a weather strip member to seal said means when in closed position.

2. In combination with the meeting rails of a pair of window sash which are spaced apart to provide a ventilation passageway between them, a plate hinged along one margin to one of the meeting rails and adapted to be swung into a position to either open or close said passageway, and a weather strip carried by the other meeting rail for engage-

ment by the free margin of said plate when in a position closing said passageway. 45

3. In combination with the meeting rails of a pair of window sash which are spaced apart to provide a ventilation passageway between them, a plate hinged along one margin to one of the meeting rails and having a flange along its other margin, and a weather strip carried by the other meeting rail and adapted to be engaged by said flange when said plate is in a position closing said passageway. 50

4. In combination with the meeting rails of a pair of window sash which are spaced apart to provide a ventilation passageway between them, a plate hinged along one margin to one of the meeting rails and adapted to be swung into a position to either close or open said passageway, a weather strip carried by the other meeting rail for engagement by the other margin of said plate when said plate is in a position closing said passageway, and a second weather strip carried on the underside of said plate and engaging the first mentioned meeting rail when said plate is in its closed position. 55

5. In combination with the meeting rails of a pair of window sash which are spaced apart to provide a ventilation passageway between them, a plate hinged along one margin to one of the meeting rails and having a flange along its free margin, a weather strip carried by the other meeting rail for engagement by said flange, and a second weather strip carried on the underside of said plate for engaging the first mentioned rail, when said plate is in a position closing said passageway. 60

In testimony that I claim the foregoing as my invention, I affix my signature this 23rd day of May, A. D. 1923.

JOSEPH SYLVAN.
